UNITED STATES PATENT OFFICE

161,333

BOOK HOLDER

James B. Gooken, Corona Del Mar, Calif.

Application July 11, 1950, Serial No. 11,067

Term of patent 14 years

(Cl. D33—2)

To all whom it may concern:

Be it known that I, James B. Gooken, a citizen of the United States of America, residing at Corona Del Mar, county of Orange, and State of California, have invented a new, original, and ornamental Design for a Book Holder, of which the following is a specification, reference being had to the accompanying drawing, forming a part thereof, wherein:

I claim:

The ornamental design for a book holder, as shown.

JAMES B. GOOKEN.
